WINDOW CONSTRUCTION

Peter Delich, Duluth, Minn.

Application March 19, 1937, Serial No. 131,910

2 Claims.

(Cl. 20—53)

This invention relates to window construction and has special reference to a preassembled unit ready for installation within the frame structure of a building from the interior thereof.

The principal object is to provide a combination of combined principal and auxiliary window frame, the auxiliary frame, carrying the window sash, being swingable or otherwise adjustably attached to the principal frame, and the latter is ultimately fixed in the building structure.

Another object is to provide a window structure that will permit of all adjustment, application, cleansing, etc., of storm window or screen as well as the cleansing and caring of the window itself from the interior of the building.

Other objects and advantages of the invention will appear in the following description thereof.

Referring now to the accompanying drawings, forming part of this application, and wherein reference characters indicate like parts:

Figure 1 is an elevation of one of the improved window units from the interior thereof and illustrating the window sashes partly open, but the auxiliary frame in closed position.

Figure 2 is a transverse section of Figure 1, however illustrating the auxiliary window frame in opened position.

Figure 3 is an enlarged section of one modified form of one side of the auxiliary frame.

Figure 4 is an enlarged transverse section on the line 4—4, Figure 2.

1 represents the jambs of the window frame proper which carries the complete and finished lower sill 2 as well as the top jamb 3, all of these being inclined and converging outwardly in respect to the unit so that freedom is provided for the action of the auxiliary window without jeopardizing the tightness of the joint between it and the principal window frame, though the jambs 4 of the auxiliary frame carrying the window sash are formed as shown in Figures 1 and 2 of the drawings, necessitating the sashes being of different widths and their edges also being inclined to coincide with that of the jambs 4; the lowermost sash being illustrated at 5 and the uppermost sash at 6.

In this construction, as seen in Figure 2 of the drawings, I have provided T-shaped metal weather strips illustrated at 7 with the view of tightening the joint between the sash and the jambs as well as the various stops, and thus dispense with the necessity of weights to counteract the gravitating effect of the sash.

The principal frame structure carries the outer trim 8 of the window and the inner edge of which projects inwardly of the inner face of the jambs 1 providing a corner between it and the jamb and in which is installed the sponge rubber or other suitable gasket 9 extending along both sides and across the top thereof. Outwardly of this gasket installation I have shown the edges of the trim as being stepped as at 12 for the reception of the storm or screen sash, it preferably being removably carried by the narrow trim 11 of the auxiliary frame, and which attachment to the auxiliary frame may be accomplished as by screws, hooks, or any other suitable means.

It is to be noted that the sill 13 carried by the auxiliary frame surmounts the sill 2 of the main frame, permitting of the inner auxiliary sill of the window as indicated at 14 being installed beneath the sill 2 and thus provide ample clearance between the upper surface of said auxiliary sill and the lower portion of the swinging auxiliary frame. It will also be noted in the preferred construction of the device I have illustrated the straps, for example, of the hinges 15 as being mortised into and extending inwardly and engaging both the inner trim 16 of the principal frame and the jamb 1, there being a similar installation of the locking member 17 covering both the jamb and the edge of the trim 16 so as to result in as sturdy and substantial unit as possible for the purpose. Thus this unit, having the full length of outer sill 2 attached thereto, may readily be placed within the wall of a building from the interior thereof without engaging the studs 18 of the wall of the building, as only the inner trim of the unit extends laterally to a greater width than the space intermediate of the studding, but inasmuch as the jambs of the principal frame are sufficient in length to provide room for the sheathing of the building as shown at 19 and the lath and plaster finish 20 of the interior, a secure and weather tight installation is readily accomplished.

In Figure 3 is illustrated a modified form of sash carrying frame in that the side jambs 21 of this frame are disposed at right angles to the sash carried therein. In this frame the sashes 22 and 23 are of the same width, and the inclined outer jamb 24 of this type of frame is spaced sufficiently from the jamb 21 to provide vertical channels 25 and 26 for the weights 27 and 28 respectively for the window sash and avoid the necessity of friction stops, as previously described, these weights being hung and func-

tioning identically with that in common practice, and there may be other modifications that would bespeak practicability of the invention without departing from the spirit thereof.

5 From the foregoing it is evident that I have devised an exceedingly simple and practical construction which avoids the necessity of any attendance being given same from the exterior of the building, and which installation thus overcomes the very dangerous practice of washing or otherwise caring for windows from the exterior of a building, which results in so many accidental deaths and injuries to human lives.

10 Having thus described my invention, what I claim and desire to secure by Letters Patent, is:

15 1. A preassembled window unit for installa-

tion within the frame structure of a building from the interior thereof comprising in combination a principal frame structure and an auxiliary sash carrying structure hingedly carried by said principal structure and characterized by having means intermediate of said structures for removably carrying an auxiliary sash.

2. In combination an outer window frame fixed within the wall of a building, an inner frame hingedly united to the outer frame and swingable inwardly therefrom, and means whereby to removably support a storm or screen sash intermediate of opposed spaced marginal edges of said frames when in closed relation.
